[57] CLAIM

What is claimed is the ornamental design for a finger ring, as shown.

DESCRIPTION

FIG. 1 is a front view of a finger ring according to my new design, the rear view being a mirror image of the front view.

FIG. 2 is a right side view thereof.

FIG. 3 is a top view thereof.

FIG. 4 is a bottom view thereof.

FIG. 5 is perspective view thereof; and,

FIG. 6 is a left side view thereof.

The broken lines are for purposes of illustration only and form no part of the claimed design.

1 Claim, 2 Drawing Sheets

FIG. 2.

FIG. 1.

FIG. 3.

FIG. 4.

FIG. 5.

FIG. 6.
